PULSE TIME MODULATION MULTIPLEX
RECEIVERDonald D. Grieg, Forest Hills, N. Y., assignor to
Federal Telephone and Radio Corporation, New
York, N. Y., a corporation of Delaware

Application March 5, 1945, Serial No. 581,037

6 Claims. (Cl. 179—15)

1

This invention relates to multi-channel communicating systems and more particularly to a system for selectively receiving and demodulating the channel pulses of a train of multi-channel pulses.

In the copending application of E. Labin-D. D. Grieg-G. J. Lehmann for Multi-channel communicating system, Serial No. 548,368, filed August 7, 1944, a multi-channel communicating system is disclosed having transmitting means at one terminal for transmitting a train of channel pulses wherein the pulses of one channel are provided with an identifying characteristic distinct from the pulses of other channels for use as synchronizing pulses. The signal pulses of the other channels are time modulated with respect to the pulses of the synchronizing channel according to signal intelligence of the respective channels. A receiving system is provided at a second terminal for receiving the train of channel pulses. The receiving system includes means for obtaining energy of the synchronizing pulses for use in selective segregation of the pulses of the different channels, and for applying the selected signal pulses to a demodulator for translation of the time modulation thereof into amplitude modulated energy.

It is an object of this invention to provide a receiver to utilize the synchronizing pulse energy of such a multi-channel train of pulses for both the selecting and demodulation of the time modulated signal pulses of the train.

Another object of the invention is to provide means for separating synchronizing or benchmark pulse energy from a train of interleaved synchronizing pulses and signal pulses and to translate the synchronizing pulse energy into a suitable signal pulse selecting and demodulating energy.

According to one feature of the invention, the synchronizing pulses, after separation from the received train of pulses are retarded in time to coincide roughly with the time modulated signal pulses of a given channel. The retarded synchronizing pulses are shaped to include a voltage variation characteristic such that when these reshaped or demodulator pulses are combined with the received train of pulses in an electric valve such as an amplifier or other suitable mixing circuit, the desired signal pulses combine with the demodulator pulses to produce composite pulses, the peaks of which represent the signal component of the signal pulses. The voltage variation of the demodulator pulses is preferably linear so that when the signal pulses are

2

superimposed thereon, they are elevated in amplitude according to the time modulation thereof.

The signal component may be obtained from the composite pulses thus formed by either a threshold clipping operation determined by the biasing of the demodulator amplifier or the signal component may be obtained by a peak riding clipper connected to the output of the demodulator or combining circuit. In conjunction with the clipping operation, a low pass filter capable of rejecting the pulse and composite pulse components is used.

Other features of the invention include various ways of effecting reshaping of the synchronizing pulse energy. A simple transformer or capacitance-resistance network may be provided to differentiate the synchronizing pulse energy to produce a pulse shape having the desired voltage variation characteristic. A multiple-vibrator circuit may also be used for this purpose, the time constants being so selected as to provide the desired pulse shapes. Still another form may comprise an harmonic selector to produce an harmonic wave of the desired frequency which, when combined with the synchronizing pulse energy, before or after retardation, will provide a composite demodulator pulse having the desired voltage variation characteristic.

For a better understanding of the objects and features of this invention, reference may be had to the following detailed description to be considered in connection with the accompanying drawings in which:

Fig. 1 is a schematic block diagram of a multi-channel receiving system according to this invention;

Figs. 2 and 3 are graphical illustrations useful in explaining the operation of the receiving system;

Figs. 4, 5 and 6 illustrate different pulse shapers that may be employed in the system of Fig. 1; and

Fig. 7 is a graphical illustration useful in explaining the operation of the system illustrated in Fig. 6.

Referring to Figs. 1 and 2 of the drawings, the receiving system shown in Fig. 1 includes a plurality of receiving channels for selective reception of the channels of a train of multi-channel pulses such as is illustrated in graph A of Fig. 2. While the train of pulses is shown to include signal channels 1, 2 and 3 besides a synchronizing channel S, it will be understood that many additional channels may be provided depending upon the length of the train cycle, the width of

the channel pulses, the maximum time modulation of the pulses and the width of guard interval required between pulses of adjacent channels.

The receiving system of Fig. 1 is shown with two receiving channels, the provision for additional channels being indicated by broken connections. The receiving system is shown, for purposes of illustration, as capable of receiving over either a direct line connection 4 through impedance matcher 5 or over a radio link by shifting switch 6 to the output connection of radio receiver 7. The received train of channel pulses may have the appearance shown in graph A of Fig. 2 or according to graph B. Graph A shows the train of pulses with interference fluctuations varying the amplitudes of the pulses. Where the system is subject to such interference, as in the case of a radio link, either the radio receiver 7 may be provided with clipping means or a separate clipper amplifier may be provided as indicated at 8 for clipping the pulse train between levels 9 and 10, thereby eliminating substantially all of the interference occurring between pulses and during pulses.

After clipping, the pulse train is applied to a synchronizing pulse selector 11 which may be of any known character capable of discriminating between pulses of two different widths. Since the synchronizing pulses are provided with a pulse width greater than the pulse width of the other channel pulses they are readily segregatable and the output, depending on the circuit or pulse shaper means that may be included in such selector circuit, may comprise wider width pulses S₁, graph C. The synchronizing pulses S₁ thus separated from the other channel pulses are applied over connection 12 to a delay network 13. The network 13 is provided with output connections 14, 15, etc., to provide different amounts of retardation from the synchronizing pulse energy in accordance with the time spacing between the pulses of the successive channels. The energy of output connection 14, which is retarded an amount t₁ for demodulation of channel pulses 1, is applied to a shaper 16 whereby the delayed pulse energy is shaped similarly as illustrated at S₂, graph D. The shaper 16 comprises a transformer of a known characteristic capable of differentiating the synchronizing pulses S₁ into the shape represented at S₂. The leading edge of each pulse S₁ produces a sharper increase in voltage and the duration of the pulse in conjunction with the time constants of the transformer produce a voltage variation decay such as indicated at 17. It is this voltage variation of the pulse S₂ that is desirable for translation of the time modulation of signal pulses.

The pulses S₂ are applied to a selecting demodulator 18 which may comprise any one of several known circuits. One common circuit that may be employed is a threshold clipping amplifier biased to cut off at a clipping level such as indicated at 19 in graph E. The signal pulse output of clipper 8 is applied over connection 8a to the demodulator 18 where the pulses thereof combine with the demodulator pulses S₂ in accordance with their timing relationship. The duration of the linear portion 17 is selected preferably to overlap the interval between the limits of modulation of the signal pulses desired. This is illustrated by the relationship shown in graph E. The signal pulse is superimposed, in effect, upon the inclined portion of the demodulator pulse thereby producing a peak corresponding to the

signal component of the time modulation of the signal pulse. These peak portions exceed the clipping level 19 and a corresponding amplified current flow is produced in the output of the demodulator 18 as indicated by pulses 1a. By applying the pulses 1a to a low pass filter 20, the pulse component is removed and the resulting audio signal is applied to phones 21 or other utilization apparatus.

10 In Fig. 3, a graph is shown illustrating the demodulation of the signal component of a particular channel such as channel 2 according to a demodulator circuit having a cut off 19' selected below the channel pulse levels. The signal pulses 15 of channel 2 are superimposed on the demodulator pulses S₂ according to the time modulation of the signal pulses, thereby producing pulse peaks which define the signal component 22 thereof. The low pass filter in this case removes the pulse formations and passes the frequencies of the signal component represented by the peak portions of the pulses 2.

15 In Fig. 4 a shaper 23 is shown comprising a capacitance 24 and a resistor 25 connected as a differentiator circuit. By proper choice of the time constants of the elements 24 and 25, the synchronizing pulses S₁ may be transformed into a demodulator pulse S₂ of the desired shape. The output of shaper 23 in this embodiment is shown applied to the selecting demodulator 18 which as shown in Fig. 4 is connected to a peak riding clipper 26. The peak riding clipper is illustrated in block form since it is of known character. The peak riding clipper operates to produce a current output corresponding in amplitude 20 to the peaks of the composite pulses such as illustrated in graph E of Fig. 2.

20 In Fig. 5, a shaper circuit 27 is indicated as of the multi-vibrator type. Since multi-vibrator circuits of the character useful in this invention are well known, no circuit diagram is necessary. The point to be made is that by selecting proper time constants for the multi-vibrator circuit, the synchronizing pulse energy S₁ may be translated 25 into a wave form, indicated at 28, having discrete pulse portions with inclined tops 29 of substantially linear characteristic capable of translating time modulation of the signal pulses.

25 In Fig. 6, I have shown a further shaper arrangement for the multiplex receiver of Fig. 1. In graph G of Fig. 7, I illustrate the train of received pulses corresponding to the train shown in graph B of Fig. 2. Graph H represents the synchronizing pulses S₁ after retardation in delay device 13 as it appears on connection 14, Fig. 6. Shaper 30 may comprise any known amplifier whereby two pulse potentials are combined for controlling the output thereof. Connection 31 of the delay device 13 is so selected as to provide a retardation of the synchronizing pulse energy substantially as indicated at S₃. The pulse output S₃ is applied to an harmonic selector 32 whereby an oscillatory or other suitable wave shape 33 is obtained, the frequency of which is 30 an harmonic of the repetition frequency of the pulses S₃. The oscillatory wave 33 is applied to the shaper 30 to mix, or in other words, combine with the pulse energy S₁ thereby producing effective demodulator pulses S₄. This pulse is the result of adding pulse S₁ to wave 33 and removing by clipping all wave energy except that of the wanted pulse S₄. It will be noted that the inclined voltage variation 34 of the pulse S₄ is opposite to the inclination of the pulses shown in Figs. 35 2, 4 and 5. It will be understood, of course, that

the retardation of pulses S_3 may be so selected as to phase the wave 33 for coincidence between the pulse S_3 and the trailing edges of the undulations of wave 33 instead of the leading edges shown.

While I have shown and described particular forms and systems by which the principles of my invention may be practiced, it is recognized that many variations may be made without departing from the invention. For example, the receiver system may be made for one channel only, and also may be used for single channel transmission such as might include, besides the signal pulses bench mark pulses similar to the synchronizing pulses S. Also the delay device may comprise circuits other than the inductance capacitance delay network shown. It is to be understood, therefore, that the forms herein shown and described are to be regarded as illustrative of the invention only and not as restricting the scope thereof as set forth in the objects and the appended claims.

I claim:

1. In a receiving system for a train of time modulated signal pulses including bench mark pulses with signal pulses interleaved therewith, means for segregating the bench mark pulses from the signal pulses and give them a substantially rectangular shape, means to retard the rectangular pulses and produce a wave having an harmonic relationship with respect to the recurrence rate of said bench mark pulses, means to phase said wave to cause a substantially linear part thereof to coincide with each of said rectangular pulses, said rectangular pulses being combined with said wave to produce discrete demodulator pulses having substantially linearly inclined top portions.

2. In a receiving system for a train of time modulated signal pulses including bench mark pulses interleaved therewith, means for segregating the bench mark pulses from the signal pulses and give them a substantially rectangular shape, means to retard the rectangular pulses, means to produce a wave having an harmonic relationship with respect to the recurrence rate of said bench mark pulses, means to phase said wave to cause a substantially linear part thereof to coincide with each of said rectangular pulses and to combine said wave and said rectangular pulses to produce discrete demodulator pulses having substantially linearly inclined top portions, and means to combine said demodulator pulses with the signal pulses to translate the time modulation of the signal pulses into amplitude modulated energy.

3. In a receiving system for receiving a desired one of a plurality of channels of time modulated pulses interleaved in sequence in the form of a single multi-channel pulse train, the pulses of one of the channels being provided with an identifying characteristic distinct from the pulses of the other channels for use as synchronizing pulses; means to separate the synchronizing pulses from said single train, means to retard the pulse energy of the synchronizing pulses of a width as great as the time modulation displacement to produce demodulator pulses timed to overlap the signal pulses of the desired channel, means to give the demodulator pulses a voltage amplitude variation characteristic and means to mix said demodulator pulses with said train of pulses, the pulses of the desired channel combining with the demodulator pulses to produce composite pulses having peaks representing the

signal component of the time modulation of the signal pulses of said desired channel.

4. A receiving system according to claim 3 wherein said means for giving said synchronizing pulses a substantially linearly inclined portion includes a means to give said synchronizing pulses a substantially rectangular shape, and a differentiator means having time constant characteristics which respond to each of said substantially rectangular pulses to produce a sharp build up potential followed by a substantially linear decay portion.

5. In a receiving system for receiving a desired one of a plurality of channels of time modulated pulses interleaved in sequence in the form of a single multi-channel pulse train, the pulses of one of the channels being provided with an identifying characteristic distinct from the pulses of the other channels for use as synchronizing pulses; means to separate the synchronizing pulses from the single train, means to retard the pulse energy of the synchronizing pulses, means to produce substantially rectangular pulses from the retarded energy, means to produce from the retarded energy a wave having an harmonic relationship with respect to the recurrence rate of said synchronizing pulses, means to combine the wave with said rectangular pulses to produce demodulator pulses having inclined tops, and means to mix said demodulator pulses with said train of pulses, the pulses of the desired channel combining with the demodulator pulses to produce composite pulses having peaks representing the signal component of the time modulation of the signal pulses of said desired channel.

6. In a multi-channel receiving system for selectively receiving a plurality of channels of time modulated pulses interleaved in sequence in the form of a single multi-channel train, the pulses of one of the channels being provided with an identifying characteristic distinct from the pulses of the other channels for use as synchronizing pulses; means to separate the synchronizing pulses from said single train, retardation means to retard by different amounts the pulse energy of the synchronizing pulses to provide different trains of demodulator pulses of a width as great as the time displacement of said modulated pulses each such train corresponding in time to one of the channels, a plurality of receiving channels each having mixer means to mix a train of demodulator pulses with said single train, and means including a shaper circuit to apply said demodulator pulses to said mixer means, said shaper circuit being arranged to vary the voltage amplitude of said demodulator pulses in a manner to elevate the voltage of the desired signal pulses according to their time modulation to produce peaks representing the signal component thereof.
